Attorney.*

UNITED STATES PATENT OFFICE.

GEORGE C. MARTIN, OF LOS ANGELES, CALIFORNIA.

IRRIGATING VALVE.

1,414,034.

Specification of Letters Patent. Patented Apr. 25, 1922.

Application filed October 7, 1920. Serial No. 415,444.

To all whom it may concern:

Be it known that I, GEORGE C. MARTIN, a citizen of the United States, and a resident of Los Angeles, in the county of Los Angeles, State of California, have invented new and useful Improvements in Irrigating Valves, of which the following is a specification.

My invention relates to and has for an object the provision of certain improvements in irrigating valves such as are used in irrigating systems for orchards and the like, and consist mainly in means for mounting the valve stem and T on the valve lid, whereby the lid may be raised and lowered with facility relative to the arm member which constitutes the valve mounting for the standpipe. Other objects may appear as the description progresses.

I have shown one practical embodiment of my invention in the accompanying drawings, in which:

Fig. 1 is a plan view of the valve apart from its support.

Fig. 2 is a bottom plan view of the same showing particularly means for locking the valve stem bushing.

Fig. 3 is an enlarged section of said locking means.

Fig. 4 is an elevation of my valve, partly in section.

Fig. 5 is a sectional elevation of a water pipe and standpipe with my valve shown attached thereto for use.

I will now describe my improvements in connection with a well known type of irrigating valve, now in general use, reference being had to the drawings hereinabove mentioned.

Referring to Fig. 5, a main irrigating pipe, or lateral P is shown in section with a standpipe S attached thereto and in communication therewith and a valve mechanism V mounted at the upper end of the standpipe. An outlet O is attached to the upper end of standpipe S and carries one or more gate valves G. This structure is common to such systems and is shown only for illustrating my improvements.

Valve V consists of a main supporting member 1, having an annular portion adapted to seat on the end of the pipe S and a depending central rib, or arm 2 which spans the opening 3 within the annular neck 4 of said supporting member. A lid, or closure 5 of disc-like character is arranged

to seat on the upper edge of the neck 4 and has a gasket 6 on the lower side thereof engaging the neck and serving to pack the joint between the neck and lid, as shown in Fig. 4.

The central portion 7 of the lid is bored to receive an extension 8 of the T 9, a flange 10 is formed on said T for affording an abutment, and a washer 11 is provided on the lower end of extension 8 for engagement with and to hold the gasket 6 on the lid. The upper portion of the T is cored to receive the end of the valve stem 12 and the lower portion thereof is threaded to receive an externally threaded bushing 13 which has a slightly enlarged head 14 on its end, said bushing being flattened as at 15, 15 on opposite sides, as shown in Figs. 2 and 4.

A lock washer 16 is held between the head 14 of said bushing and the end of extension 8 and has a square opening 17 therethrough which fits over the flats of the bushing, and the periphery of the lock washer substantially overlaps the washer 11 and gasket 6, as shown. When the bushing 13 is tightened in the T by suitable means the same is adapted to be locked against turning by means of lips 18, 18 formed on the inner portion of the lock washer 16 adjacent to the flat sides 15 of the bushing. Said lips are forced inwardly into recesses 19, 19 in the end of extension 8 of the T, as shown in Fig. 3 and thus the bushing and T are locked against accidental separation in use. The valve stem 12 is carried in the central portion of the arm 2 and has a head 20 on its lower end and a lock nut 21 above the portion 22 of said arm, and is thus rendered stationary in its support. This valve stem preferably has a square thread and is threaded through the bushing 13 which has a corresponding thread. Said bushing is preferably of bronze or other non-corroding metal and the stem is usually galvanized so as to prevent rusting and the consequent difficulty in operating the valve after long usage as would otherwise occur.

The operation of the valve is well understood. The T 9 is rotated manually on the stem 12 and the lid 5, gasket 6, washer 11 and bushing 13 rotate therewith at all times, the said members being elevated or lowered relative to the neck 4, according to the direction in which they are turned, and the pipe S is opened or closed, as the case may be, correspondingly.

2
What I claim, is:

1. In an irrigating valve, a stationary valve stem, a closure member operable thereon and including an operating member having a threaded bushing therein, and means intermediate said operating member and said bushing for rendering the bushing movable with said closure.
2. In an irrigating valve, a valve stem, a closure member having a handle thereon and movable relative to said stem, a bushing of non-corrodible material held on said closure and threaded to receive said stem, and a locking member carried on said bushing and having means engaging a portion of said closure member, for effecting the simultaneous movement of said bushing and said closure member.
3. An irrigating valve including relatively movable valve stem and closure members, a bushing carried in said closure member and threaded to receive said stem, and a locking disc held between a portion of said bushing and said closure member and having means for locking said elements together for use.
4. An irrigating valve including a valve support, a relatively movable valve stem and closure held thereon, a bushing held on said closure and threaded to receive said stem, said bushing having an enlargement at one end, and a locking disc held on said bush-

ing and between said enlargement and said closure and having portions seating in said closure, for the purpose described.

5. An irrigating valve having a valve stem and a closure movable thereon, a T attached to said closure, a bushing threaded into said T and having flattened portions on its periphery, a locking member having an opening with flat sides engaging the flattened portions of said bushing, said T having recesses in the end thereof, and said locking member having lips adapted to seat in said recesses, for the purpose described.

6. An irrigating valve having a valve stem and a closure movable thereon, a bushing threaded into a portion of said closure and internally threaded to receive said valve stem, said bushing having flattened portions on its periphery and an enlarged head, a locking member carried on said bushing and having a rectangular opening therein to receive said bushing and engaging said flattened portions, said closure having recesses formed adjacent to said locking member, and said locking member having lips adapted to seat in said recesses, for locking said bushing and said closure together for operation
